P. G. GARDINER.

Car Axle.

No. 14,232.

Patented Feb. 12, 1856.

UNITED STATES PATENT OFFICE.

P. G. GARDINER, OF NEW YORK, N. Y.

RAILROAD-CAR AXLE.

Specification of Letters Patent No. 14,232, dated February 12, 1856.

To all whom it may concern:

Be it known that I, P. G. GARDINER, of the city, county, and State of New York, have invented a new and Improved Car-Axle; and I do hereby declare that the following is a full and exact description thereof, reference being had to the accompanying drawings, making a part of this specification.

10 Figure 1, is a side view of my improved car-axle; Fig. 2, a longitudinal section of a portion of said axle; and Fig. 3, a transverse section of the same, in the line *c, d*, of Fig. 2.

15 My improved car-axle is constructed in the following manner; viz; a sheet of metal *a*, of proper length, width, and thickness, is bent into the form of a tube, by giving it one, two, or more turns around a mandrel, 20 and then the ends of said tube are welded to solid journal-pieces *b, b*. The surfaces of the said sheet of metal are left unconnected,

save at the ends of the sheet, where they are solidly welded to the journal-pieces *b, b*, which causes the central portion of the axle 25 to be elastic in a winding direction, and thereby prevent any injurious torsion strain from being exerted upon any portion of the axle, when subjected to the most violent usage.

30 What I claim as my invention and desire to secure by Letters Patent is—

My improved car-axle, composed of a sheet of metal wound into a tubular form with its ends welded to solid journal-pieces, 35 substantially as herein set forth.

The above specification of my new and improved tubular car-axle signed and witnessed this 20th day of November A. D. 1855.

P. G. GARDINER.
